P. A. Blair

Attorney

UNITED STATES PATENT OFFICE.

EDWIN COWLES, OF NEW YORK, N. Y.

PORTABLE WASHING MACHINE.

Application filed June 28, 1923. Serial No. 648,256.

To all whom it may concern:

Be it known that I, EDWIN COWLES, a citizen of the United States, residing at New York, in the county of New York and State 5 of New York, have invented certain new and useful Improvements in Portable Washing Machines, of which the following is a specification.

This invention relates to improvements 10 in washing machines, and more particularly to that general type illustrated in my co-pending application, Serial No. 588,271, filed September 14, 1922.

One of the objects of the present invention 15 is to provide a simple and practical washing machine particularly adapted for household use, which may be easily operated.

A further object is to provide an apparatus of the above general character having 20 relatively few parts, which may be inexpensively manufactured and assembled.

Another object is to provide a portable self-contained washing machine which may be placed in any fluid-tight receptacle containing 25 the clothes or articles to be washed and operated from any convenient source of power.

A further object is to provide a practical, self-contained portable washing apparatus, 30 requiring a minimum amount of attention in its operation and one which will be "foolproof."

A further object is to provide a washing machine of the above character which will 35 reliably and efficiently clean the clothes acted upon by it, without danger of the clothes becoming clogged or matted during the washing thereof.

Other objects will be in part obvious and 40 in part hereinafter pointed out in connection with the accompanying sheet of drawings showing one of various possible embodiments of the invention, and in the several views of which similar parts are designated by corresponding reference characters.

In the accompanying drawings,—

Figure 1 is an elevational view showing the complete apparatus;

Figure 2 is a detail view, certain parts 50 being broken away or shown in section to more clearly illustrate the same; and

Figure 3 is a detail sectional plan view.

Referring now to these drawings in detail, and more particularly to Figure 1, 5 indicates a motor of small horsepower, preferably electric, and either of universal type,

A. C. or D. C., as may be desired, according to the lighting circuit of the city in which the article is to be used. This motor is rigidly supported by a plurality of supporting legs 6 directly associated with a top plate 7 secured in any desired manner, as by means of small screws 8 to the upper part of a cylindrical casing 10, the lower part of which is provided with an open face 60 11 in the present instance, formed of a stit-able screen or relatively close perforations, directly in the wall of the cylinder 10.

This cylinder has a plurality of perforations or a screen forming an "open face" 11, 70 as it may be termed, and associated therewith, in the present form, is an outlet or nozzle 12 which is connected to the discharge of a rotary pump 13 shown more clearly in Figures 2 and 3. This pump is of any 75 desired conventional form operated by means of a shaft 14 directly connected with the motor 5. The underside of the pump is preferably spaced two or three inches from the bottom of the casing 10 and is provided with an opening 15, whereby the water is drawn into the central part of the pump through the open face 11, and ejected forcibly through the nozzle 12.

In practice, I prefer to locate this nozzle 80 12 in the center of the open face 11, thereby to act directly upon the clothes being washed and to force them away from the openings. This positively prevents the clothes from clogging or matting against the 85 open face, which it will be observed is the suction end of the circulating system. While the exact location of this nozzle with respect to the open face is not essential, it is, however, the more desired form, for this nozzle 90 should be so disposed with respect thereto as to positively prevent the clothes from matting thereagainst.

It will be noted that some of the openings in the open face 11 are above the nozzle 12, 100 whereby the water is drawn in through the upper part of the open face as well, thereby to lubricate the bearing of the rod 14 as it passes through a suitable boss 16 in the upper part of the pump casing.

While the construction of the above device is perfectly clear from this description, a brief statement of the operation is as follows:

The motor is connected by means of flexible cord 17 and the usual plug with any desired source of electric current, such as a

lighting fixture. The casing or cylinder 10 is placed in a tub or bucket of water or even a wash basin, in which the clothes to be washed are also to be placed. The current is then turned on and the motor drives the shaft 14 at a high rate of speed, causing the pump 13 to revolve and draw the wash water in through the perforations 11 up through the opening 15 on the under-
10 side of the pump from which circulating system it is ejected forcibly through the nozzle 12. This high pressure jet of water not only thoroughly cleans the clothes, but causes them to circulate rapidly about the receptacle and also positively prevents them from matting against the suction openings.

The device is of simple and practical construction, is self-contained and easily carried from one place to another, and can be
20 conveniently set up in any receptacle at a moment's notice. It will, therefore, be seen that the present invention fully contemplates among others all of the objects and advantages herein set forth.

25 Without further analysis, the foregoing will so fully reveal the gist of this invention that others can, by applying current knowledge, readily adapt it for various applications without omitting certain features
30 that, from the standpoint of the prior art, fairly constitute essential characteristics of the generic or specific aspects of this invention, and, therefore, such adaptions should and are intended to be comprehended within
35 the meaning and range of equivalency of the following claims.

I claim:

40 1. In a portable self-contained washing machine, in combination, a member adapted to be placed in a receptacle and having an open suction face, a pump directly associated therewith for drawing water in through said open face, and a discharge nozzle associated with said pump so positioned with
45 respect to said open face as to positively prevent the clothes from matting against the suction opening.

2. In a portable self-contained washing

50 machine, in combination, a body member having a motor directly associated therewith, a pump carried within said body member, a suction opening in the body member for supplying fluid to the pump, a discharge nozzle connected with said pump and so positioned with respect to said suction opening as to prevent the clothes from matting thereagainst.

55 3. In a portable self-contained washing machine, in combination, a body member having a motor directly associated therewith, a pump carried by said body member, a suction opening in the body member for supplying fluid to the pump, a discharge nozzle connected with said pump and so positioned with respect to said suction opening as to prevent the clothes from matting thereagainst, said suction opening comprising a screen or perforated surface in the body member.

60 4. In a portable self-contained washing machine, in combination, a cylindrical body member having a top plate, a motor mounted directly thereon, a driving shaft extending from the motor through said top plate to the interior of the body member, and a pump driven by said shaft, said body member having an open face and a discharge nozzle associated with said open face, whereby water is drawn in through the open face and
65 forcibly ejected under high pressure through said nozzle.

70 5. In a portable self-contained washing machine, in combination, a body member, a top plate mounted thereon, a motor carried by said top plate, a shaft extending from the motor through said top plate, and a pump driven by said shaft within the body member, said body member having a plurality of suction openings, and a discharge nozzle centrally associated therewith whereby water is drawn in through said openings and ejected from said nozzle by action of the pump to prevent the clothes from matting
75 thereagainst.

80 Signed this 24th day of May, 1923.

85 EDWIN COWLES.
